(57) **CLAIM**

The ornamental design for a pull grip feature of a container lid, as shown and described.

DESCRIPTION

FIG. 1 is a perspective view of the pull grip feature of a container lid, with the container lid shown in broken lines; FIG. 2 is an enlarged perspective view of our design for a pull grip feature of a container lid as shown in FIG. 1; FIG. 3 is a front view of the pull grip feature of a container lid of FIG. 2; FIG. 4 is a back view of the pull grip feature of a container lid of FIG. 2; FIG. 5 is a left side view of the pull grip feature of a container lid of FIG. 2, the right side view being a mirror image thereof; FIG. 6 is a top view of the pull grip feature of a container lid of FIG. 2; and, FIG. 7 is a bottom view of the pull grip feature of a container lid of FIG. 2. The broken lines shown throughout these figures illustrate environmental subject matter only and form no part of the claimed design.
